(57) **CLAIM**

The ornamental design for a hexagonal wire shelf, as shown and described.

DESCRIPTION

FIG. 1 is a front perspective view of a hexagonal wire shelf;
 FIG. 2 is a rear elevation view thereof;
 FIG. 3 is a front elevation view thereof;
 FIG. 4 is a top view thereof, with the bottom view being a mirror image thereof; and,
 FIG. 5 is a left side elevation view thereof, with the right side elevation view being a mirror image thereof.
